WITNESS:

R. E. Wise.

Harold Alfred Lee

INVENTOR

BY Victor J. Evans

ATTORNEY

UNITED STATES PATENT OFFICE.

HAROLD A. LEE, OF SUVA, FIJI.

FASTENER BAR.

Application filed October 29, 1923. Serial No. 671,527.

To all whom it may concern:

Be it known that I, HAROLD ALFRED LEE, a British subject, residing at Suva, Fiji, have invented new and useful Fastener Bars, 5 of which the following is a specification.

My present invention has reference to a fastening or clamping bar designed to be passed through the eyes of shirt, vest and other buttons for holding the same on the 10 garment and to permit of the removal of the studs or buttons when the garment is being washed or otherwise cleaned.

An object of this invention is to simplify and improve the existing art by producing 15 a fastener bar of this character which shall effectively grip the eye of a button or stud to prevent the accidental disassociation of these parts, and wherein the bar may be readily removed from the eye when desired.

20 To the attainment of the foregoing, the invention consists in the improvement as hereinafter described and definitely claimed.

In the drawing:—

Figure 1 is a rear elevation of a button 25 having its eye engaged by a bar in accordance with this invention.

Figure 2 is a sectional view on the line 2—2 of Figure 1.

Figure 3 is a plan view of the bar.

30 Figures 4, 5, 6 and 7 illustrate modifications.

In the drawing, a stud or button is indicated by the numeral 1, the same being provided with the usual eye 2.

35 In all of the illustrated forms of my improved fastening bar, the same is constructed from a single piece of resilient but strong wire of a proper gauge. In the forms illustrated in Figures 1, 2 and 3 the bar includes an arm 3 rounded upon itself, as at 4, continued at a downward angle toward the bar proper, as at 5, but out of contact therewith. The angle portion 5 has its end bent to provide a hook 6, the beak of the hook 45 having its outer end beveled, as at 7 to provide the same with a pointed end, the said beveled or pointed portion resting against one side of the bar 3. The bar 3 is moved through the eye, and the eye contacting with 50 the angle portion 7 of the hook 6 will move the same away from the bar 3 to permit of the passage of the eye 2, and thereafter the resilient arm 5 of the hook 6 will force its angle end 7 against the bar 3, so that the 55 accidental removal of the button is thus pre-

vented. By exerting a pressure between the body portion or bar 3 of the device and the angle portion 5 thereof the hook will be brought away from the body 3 so that the same can be slid over the eye of the button. 60

In Figure 4, the bar is indicated by the numeral 8, the same having one of its ends rounded upon itself, as at 9 and directed angularly over the bar 8, as at 10. This angle portion terminates in a hook 11, and 65 the beak of this hook is beveled, as at 12 to contact with one side of the bar 8. The method of applying and removing is substantially similar to that previously described, but in this instance, the hook 12 70 may be moved laterally with respect to the bar 8 to permit of the removal of the eye from the fastening or holding bar.

In Figure 5, the bar proper or body of the fastener is indicated by the numeral 13, 75 the same having one of its ends rounded, as at 14, and extended inwardly into contacting engagement with the bar 13, as indicated by the numeral 15. From the portion 15 the bar is formed with a U-shaped hook 16, the 80 beak of the hook having its outer surface beveled or pointed for contacting engagement with the bar 13.

In Figure 6, the construction is substantially similar to that just described. The 85 bar 17 is rounded outwardly upon itself at one of its ends, as at 18, the said rounded portion being directed toward the bar proper and continued for a considerable distance in contacting engagement with the said bar 90 as indicated by the numeral 19. The portion 19 terminates in a hook 20 which has its end or beak beveled or pointed for contacting engagement with the side of the bar against which the portion 19 rests. In every 95 instance the U-shaped hook of the fasteners are directed angularly with respect to the body portion or bar proper and the outer elements or beaks of the said hooks are arranged at an inward inclination with respect to the bar proper. The beveled ends of the hooks are retained in contacting engagement with the bar proper by the resiliency exerted thereagainst by the rounded 100 ends of the said bar. 105

In Figure 7 a further modified form of my improvement is shown attached to a badge 21. The longer arm 22 of the fastener is passed through eyes 23 and 24 on the back 110 of the badge 21. The arm 22 has one end

coiled upon itself, as at 25 and from thence continued in a plane with the arm 22, as indicated by the numeral 26. The arm 26 is rounded and directed toward the arm 22. 5 This rounded portion provides a spring beak 27 which is arranged to contact with the upper eye 23 of the badge.

It is believed that the foregoing description, when taken in connection with the drawing will fully set forth the construction 10 and advantages of the improvements to those skilled in the art to which the invention relates so that further detailed description will not be required.

Having described the invention, I claim:— 15

A button or stud fastener formed from a strand of spring wire to include a straight substantially elongated body portion which has one of its ends rounded and brought to contact with the body and terminates in an 20 outwardly directed U-shaped portion whose outer arm is beveled to provide a pointed end which is in frictional engagement with the body.

In testimony whereof I affix my signa- 25
ture.

HAROLD A. LEE.
